EMIL SINNER, OF MILWAUKEE, WISCONSIN, ASSIGNOR TO CLUM MANUFACTURING COMPANY, OF MILWAUKEE, WISCONSIN, A CORPORATION

SWITCH

Application filed March 12, 1931. Serial No. 521,934.

This invention relates to improvements in switches.

It is the primary object of the invention to provide a novel and improved switch structure in which changes from one lighting position to another are effected without interrupting the circuit controlled in one switch position until the circuit controlled in the next position of the switch has been closed. It is particularly true of under-column switches that the resilient torsion in the controls extending the length of the steering column makes the switch positions less perceptible than would be the case if the torsional resilience were eliminated. In some instances this has led to misapprehension on the part of drivers as to the condition of their lights, and the switch has been left in an intermediate position in which no circuits were closed. The present invention eliminates the possibility of such an occurrence by ensuring that some switch circuit is closed in all positions of the moving switch contactor except the "off" position thereof.

A further object of the invention is to introduce great economies into the manufacture of a switch of this type. It is my purpose to provide a contact organization in which the fixed contacts are cheaper than the tubular rivets previously employed in floating contact switches; to eliminate any necessity for the use of more than one piece of bakelite or other dielectric material in the terminal head; to eliminate any necessity for fitting the fixed contacts to openings in the terminal head; to greatly reduce the cost of manufacture of the moving contact by eliminating any necessity for accurate finish of the contact surface; and to make possible for the first time the standardization of switches of this type to such an extent that a single terminal head is adapted to meet automotive requirements.

It is my further object to provide a switch in which positioning is effected by the interengagement of the contacts, but in which the spherical contact members are fixed and a floating resilient strip is provided with integral socketed members engageable over a single contact but having sufficient width so as to maintain engagement with one or both of two adjacent contacts in the course of its manipulation from one switch position to another.

In the drawing:

Figure 1 is a front elevation of the switch mechanism embodying this invention, no case being shown.

Figure 2 is a rear elevation of the switch mechanism shown in Figure 1.

Figure 3 is a developed view in section taken on the arc indicated at 3-3 in Figure 1, showing the moving contactor spanning the fixed contacts.

Figure 4 is a view similar to Figure 3, showing the moving contactor in its normal engagement with fixed contacts in an operative switch position.

Figure 5 is a fragmentary detail in enlarged perspective, showing the end of the floating contact member and a portion of the male die member by which the concave contact surface is formed, and the center punched up to provide a spring guide.

Like parts are identified by the same reference characters throughout the several views.

In switches of the floating contactor type, where engagement of the contacts has been depended upon to fix tangibly the various positions of the switches, it has been customary in the past to use tubular rivets or socketed rivets for the fixed contacts. In contrast to that policy the dielectric terminal head 5 of the present switch is provided with terminals 6 which comprise ordinary rivets with their spherical heads inwardly disposed to function as fixed contacts for the switch. At the back of the terminal head each of the live contact rivets 6 engages a terminal post 7 or a post 8 to which two contacts are connected. The dead contacts are represented by rivets 9, which are identical with rivets 6 except that they are slightly shorter because they are not required to retain a terminal post upon the terminal head.

In accordance with common practice in under-column switches, the switch control shaft comprises a tube 10 extending through the switch and carrying a jamb nut 11 at the back of the switch for contracting the slotted end portion of tube 10 upon a motion transmitting shaft from the switch control. The end of shaft 10 shown in Figure 1 is riveted over a segmental metal plate 12 which serves as a contact actuator, and is provided at its periphery with clamping tongues 13 retaining a pair of super-imposed

segmental fiber or bakelite members 14 and 15. The upper piece of bakelite or fiber 14 is provided to insulate the moving contact from the actuator plate 12. The lower piece 5 of fiber or bakelite is apertured to provide spring sockets 16 and carries studs 17 for supporting and guiding the arcuately formed resilient contactor strip 20.

Whereas the contact bosses of flexible 10 strips, such as that shown at 20, have heretofore been convex or planiform, the bosses of the present contact strip have concave contact surfaces at 21, thereby effecting important economies and advantages.

15 In the first place, the male die itself forms the finished contact surface, thereby eliminating any necessity for accurate finish on the convex rear surface of the contact. In the second place, the portion of the contact 20 adjacent its axis need not be finished at all in this construction, and is simply punched through to provide a sleeve at 22 which functions as a spring guide. In the third place, the contact boss generically designated at 25 23 is made sufficiently wide so that in all intermediate switch positions it will span the space between two adjacent contacts. In this connection the flexibility of the strip 20 is enhanced by making its curves of relatively large radius, the resulting contact carrier being sufficiently flexible so that the surface areas of its bosses will follow the contours of the fixed contacts and remain in engagement therewith over a very substantial 30 portion of the path of travel. This flexibility is illustrated in Figure 4, which shows the positions assumed by the ends of contact strip 20 when the free ends are unsupported by the contacts. The compression 35 springs 24 seated in sockets 16 act on the contacts at all times to press them in the direction of terminal head 5, and in the event of removal of the terminal head the enlarged ends of posts 17 maintain the parts in assembly.

It will be obvious to those skilled in the art that the switch herein disclosed may be provided with any desired type of case.

In the particular switch selected for the 50 purpose of illustrating the invention the neutral switch position in which all circuits are open is that position in which the three contact protuberances or convolutions 23 of the moving contactor 20 register with the three dead contacts 9 of the terminal head 5. As soon as any movement of the contactor 20 occurs with reference to the terminal head a circuit is almost immediately closed due to the extent of the contact members 23 along the path of contact movement. The pressure of springs 24 is such, however, that further movement of the moving contactor is resisted by the necessity of forcing the contact members onto the tops of the 55 spherically rounded heads of rivets 6 and 7.

It is only when a contact member exactly registers with one of the rivet heads that the firm seating is obtained which gives to the operator tangible indication of the fact that an operative switch position has been 70 reached. To prevent any such indication from occurring between stations of the switch the moving contactors should each have an extent in the direction of switch travel sufficient to span two adjacent fixed 75 contacts so that nowhere except in an operative switch station can springs 24 expand.

The danger point in switch operation has heretofore been primarily the position in which one of the moving contacts was intermediate the terminals respectively designated as "Head" and "Dim." It is very important that the lights should not be extinguished at any point in this traverse. It will be obvious to those skilled in the art 80 that this desirable result is accomplished in the present construction.

I claim:

1. In a switch having complementary fixed and movable contacts defining tangible 90 operative positions, the combination with a terminal head and a series of convex contacts mounted thereon, of a flexible contact carrier movable with respect to said head, concave contact members movable with said carrier, and means acting independently on said members for maintaining resilient pressure engagement between the contacts of the carrier and the contacts of the head.

2. In a switch, a moving contactor comprising an arcuate strip having spaced projecting contact convolutions, each of which has a recessed contact surface.

3. In a switch, a moving contactor comprising an arcuate strip having spaced projecting contact convolutions, each of which has a recessed contact surface, and a rearwardly projecting sleeve comprising a spring guide.

4. In a switch, the combination with a terminal head provided with live and dead contacts, each of which has a spherical head disposed in spaced relation in a common arcuate series with reference to the arcuate heads of other contacts, of a contact carrier movable with respect to said terminal head, an arcuate flexible contact strip yieldably mounted with respect to said head and having spaced contact convolutions individually recessed and terminating in rearwardly projecting tubular studs, and springs interposed between said contact carrier and said studs and pressing the individual convolutions of said strip into operative engagement with the rounded heads of the contacts of said terminal head, each convolution of said strip having sufficient arcuate extent to span two successive contacts of said terminal head.

5. In a switch, the combination with

spaced convex terminal contacts, of a rotatable contactor comprising a flexible arcuate strip having convolutions with recesses to engage over one of said terminal contacts of a sufficient extent in the direction of contactor movement to span the distance between centers of said terminal contacts, the backs of said recesses forming projections, each engaged with a spring disposed to press 10 its individual convolution into engagement with said terminal contacts.

6. In a switch, the combination with a pair of relatively movable contact carriers, one of which comprises a terminal head, of a series of mutually insulated convex terminal contacts carried by said terminal head, and a strip contactor guided from the other contact carrier and provided with resilient support therefrom, said contactor strip having contact convolutions offset toward said terminal head and each of sufficient extent in their direction of movement to span the distance between the tops of adjacent terminal contacts, each of said convolutions being recessed to receive a portion of a terminal contact registering with the recess.

7. In a switch, the combination with a dielectric terminal head and a dielectric contact actuator mounted for rotation with respect to said head, of terminal contacts arranged in spaced series in said terminal head and provided with projecting convex contact surfaces, a floating contact strip provided with springs resiliently supporting it from the movable contact carrier, and means constraining it for movement therewith, said strip having convolutions arranged to register with successive terminal contacts, each convolution having a contact receiving recess and a rearwardly projecting spring guide formed from the bottom of the recess and each guide being so constituted as to locate one of the above mentioned springs in predetermined relation to one of said convolutions, each convolution having an arcuate extent at least sufficient to span the spaces between consecutive terminal contacts of said series.

8. In a switch, the combination with a contact spring, of a contact comprising a yieldably mounted concavely embossed member punched up to provide a spring guide, the spring engaging said member about said guide.

55 9. In a switch, a moving contactor comprising a sheet of metal embossed to provide a concave contact surface and punched up at an intermediate point in said surface to provide a sleeve projecting rearwardly from said surface and comprising a spring guide.

60 10. In a switch, the combination with a terminal head providing a series of spaced contacts, of a moving contactor comprising

a strip and means guiding said strip for movement along the contacts of said series, said strip being flexible and formed at a plurality of points intermediate its ends to provide contact portions offset to a position for interaction with the contacts of said terminal head, each of the offset portions of said strip having a sufficient length to span the space between two successive terminals of said head for simultaneous engagement therewith, and the flexibility of said strip being such as to permit its offset portions to adjust themselves independently of the remainder of said strip for simultaneous engagement with two successive terminals of said head in the course of the movement of said strip, together with springs used individually on the offset portions of said strip to press said portions toward the terminal head.

11. In a switch, the combination with a terminal head provided with spaced projecting contacts, of a flexible contact strip provided with means for floatingly constraining it for movement with respect to said head along the series of contacts, said strip having spaced contact convolutions offset from the strip in the direction of said head and of sufficient length to engage a single contact of said head when in registry therewith, and to span two successive contacts of said head for simultaneous engagement thereof in the course of its movement with respect to said head, and compression springs engaging each of the offset portions of said strip and individually pressing each respective portion toward said head and the contacts therefor.

12. In a switch, the combination with a terminal head provided with spaced projecting contacts, of a flexible contact strip provided with means for floatingly constraining it for movement with respect to said head along the series of contacts, said strip having spaced contact convolutions offset from the strip in the direction of said head and of sufficient length to engage a single contact of said head when in registry therewith, and to span two successive contacts of said head for simultaneous engagement thereof in the course of its movement with respect to said head, and compression springs engaging each of the offset portions of said strip and individually pressing each respective portion toward said head and the contacts therefor, the convolutions of said strip being formed to provide seats engaged by the springs, and said strip being sufficiently flexible to permit each convolution to adjust itself in passing over the contacts of said head independently of the remainder of the strip.
